FLUID DRIVEN MOTOR

Harold B. Rice, Walnut Creek, Calif., assignor to John Burton Machine Corporation, Concord, Calif.
Filed Feb. 14, 1962, Ser. No. 173,279
1 Claim. (Cl. 253—2)

This application relates to a fluid driven motor employing the principle of the device disclosed in application Serial No. 3,205, filed January 8, 1960, now Patent No. 3,097,554.

In the copending application there is disclosed a fluid driven mechanism that is adapted for use as a motor and which has particular application to a driving means for a tool. In general, the invention disclosed in the copending application comprises a casing in which a rotor is floatingly mounted, and orbital movement of the rotor is achieved by a tangentially directed jet of fluid within the casing.

The present invention is an improvement on the previously disclosed device in that it provides a rotatably mounted shaft which cooperates with the floatingly mounted rotor to permit rotation of the shaft as the rotor is driven through its orbital movement.

The main object of the present invention is therefore the provision of a motor which includes an output shaft adapted to be driven by an orbitally moving fluid driven motor so that said shaft may be employed as the driving member of a tool or may be used to do other useful work.

Another object of the invention is the provision of a motor construction that is extremely simple to manufacture; that is efficient in operation without close tolerances, and is particularly adapted for use in applications wherein rough usage and abrasion is experienced.

Still another object of the invention is the provision of a motor which consists generally of a casing, a driven shaft and a plurality of rotors, assembled so as to take advantage of the simplicity characteristic of the device disclosed in the above noted copending application.

Other objects and advantages will be apparent from the following specification and from the drawings wherein:

FIG. 1 is a side elevation of a motor constructed in accordance with the invention, broken away and in section to show internal structure. The motor is shown in combination with a well drilling bit.

FIGS. 2, 3, 4 are cross sectional views as taken in planes indicated by corresponding numerals in FIG. 1, and

FIG. 5 is a fragmentary longitudinal section of a motor showing a modified form thereof.

The invention is adapted for use with any fluid including liquid and gas, but will be described by way of example as used to drive a well drilling bit of the type employed to drill oil wells. It will subsequently be apparent that the invention is particularly applicable to well drilling because the fluid under pressure which is used to drive the motor may be discharged from the motor so as to carry the cuttings away from the drilling bit in much the same manner as in conventional turbodrills.

Turbodrills have heretofore had only a limited use in this country although the principle involved in the use of such turbodrills is sound. The soundness of the principle follows from the fact that the cutting fluid which must be used to carry away the cuttings is employed to do useful work in driving the turbodrill before it is directed on the bit. The lack of success of turbodrills for drilling oil wells in this country is attributable in part to the relatively delicate nature of the turbine which is exposed to the abrasive action of the drilling mud.

2

Furthermore, the various cooperating parts of the turbine must, of necessity, be made to close tolerances, thus increasing the cost of manufacture and enhancing the likelihood of injury to the turbine which is normally subject to rough usage.

As will be seen, the present invention is ideal as a substitute for turbodrills because of its extreme simplicity and because it lends itself to a construction which practically defies wear and which is operable at relatively high efficiency even with wide tolerance in the various parts.

In detail, and first with reference to FIG. 1, the preferred form of the invention comprises a casing generally designated 1 which is formed intermediate its ends by a plurality of transverse walls 2 spaced apart by annular rings 3.

There are six identical rings 3 and seven identical walls 2 shown in FIG. 1 so as to form six power cylinders. The casing is completed by a top wall 6 and a bottom wall 7. For the purpose of well drilling a lifting eye 10 may be fastened to top wall 6 by bolts 11 so that the cylinder may be supported from a cable (not shown) by means of any appropriate wire rope connector 12.

It will be seen that each pair of adjacent walls 2 and the ring 3 that is interposed between them define a power cylinder 15, so that said walls 2 are, in effect, endwalls of the cylinders and the ring 3 constitutes a sidewall.

Each endwall 2 is provided with a central opening 16 which permits passage therethrough of a shaft 20 which is rotatably supported at its upper end in a thrust bearing 21 carried by top wall 6, and at its lower end in a thrust bearing 22 carried by bottom wall 7.

The top and bottom walls 6, 7 and the intermediate endwalls 2 and sidewalls 3 of the casing are all fixedly secured together by bolts 25 which extend through holes formed in the above mentioned casing forming elements and which are tightened on the parts by nuts 26 (FIG. 1).

As best seen in FIGS. 2-4, three bolts 25 are indicated in the drawings but a greater number may obviously be employed if required.

Each of the casing forming elements, except lowermost endwall 2 and bottom wall 7, is drilled to form an axially extending passageway 28 opening outwardly of the top wall 6 and provided with a fitting 30 on top wall 6 (FIG. 1) for securing thereto of a flexible hose 31 or other suitable conduit for conducting fluid to passageway 28.

The fluid is conducted from passageway 28 into each of the power cylinders 15 through transversely extending passageways 35 which enter the cylinders 15 tangentially of the inner cylindrical side 36 of the sidewalls 3. As indicated in FIG. 1 these passageways 35 may be conveniently formed by drilling through the axially extending bore 28 from the outer periphery of the sidewalls 3 in the required direction and then inserting a plug 37 in the outer end of each passageway 35 as by welding. It will be apparent the inner discharge ends of the transverse passageways 35 may be formed to an exact shape consistent with accepted nozzle design taking into account the particular variables applicable. However, for the purpose of this invention the exact design of the nozzle portions of passageways 35 is not disclosed except that the jet discharged from passageway 35 should be directed substantially tangentially of the inner sidewalls 3.

Mounted on the shaft 20 are a plurality of rotors 40 each of which is keyed to said shaft as by a key 41 so as to permit shifting of the rotors 40 relative to the shaft 20 in an axial direction but insuring rotation of the rotors with the shaft.

As best seen in FIGS. 2-4, adjacent rotors of the lower three are eccentric to the shaft but the angles of eccentricity are 120 degrees apart so as to result in a balanced mechanism. Similarly, the upper three rotors are eccentric and balanced, with the two central rotors of the motor being identically positioned relative to the shaft. This particular method of balancing the motor is shown only as one example and other methods may be applied consistent with good engineering practice.

To reduce fluid friction it is desirable to recess the opposite circular sides of the rotors 40 centrally of the same to provide annular faces 45 adjacent the periphery thereof. For the purpose of permitting exhaust fluid to flow axially of the motor each rotor 40 is drilled with axially extending holes 46 spaced radially inwardly from annular face 45.

As noted above, the plates 2 which constitute endwalls for adjacent power cylinders are provided with central openings 16 through which shaft 20 is received. These openings 16 are sufficiently large to permit unrestricted passage of fluid axially of the motor from one power cylinder to another. In the form of the invention shown in FIG. 1 fluid discharged through nozzles 35 into each power cylinder flows radially inwardly between the rotor and the adjacent endwalls and may then flow downwardly through openings 16 in the endwalls 2 and holes 46 in the rotors. The bottom plate 7 is provided with a plurality of discharge openings 50 arranged around bearing 22 and is also provided with an upwardly opening central recess 51 through which the discharge fluid is conducted from the opening 16 in the lowermost endwall 2 to the discharge openings 50.

It will be seen from FIG. 1 that the holes 50 may be drilled at an angle so as to direct the fluid on cutting elements 53 of the drilling bit 54.

In operation, the drilling mud, or whatever fluid is employed, is conducted through hose 31 to axially extending passageway 28 from which the fluid branches off to each of the power cylinders through the transverse passageways 35. As explained in copending application Serial No. 3,205, the tangentially directed fluid from passageways 35 drives the rotors 40 in a clockwise direction as seen in FIGS. 2-4 and thus turns shaft 20. It will be noted in the instant case that the amount of eccentricity of each rotor relative to shaft 20 is such that the rotor just clears the inner cylindrical surface 36 of the sidewall 3 and does not tend to roll on said surface as would be the case if shaft 20 were not rotatably supported on a fixed axis. However, the behavior of each rotor is substantially the same as described in the copending application in that the fluid continuously flows radially inwardly along the opposite sides of the rotor so that the rotor is floatingly mounted and does not come in contact with any adjacent surface while the motor is running. It will be understood that the keys 41 on shaft 20 permit axial movement of the rotors so that the fluid may flow past both sides of the same; the distance between adjacent endwall plates 2 being sufficiently greater than the thickness of each rotor to provide ample space for relatively unobstructed flow of fluid radially inwardly of each power cylinder.

Although drilling mud may include solid particles in suspension it will be noted that the clearances between relatively moving parts of the motor may be great enough so that no galling is likely to occur. Furthermore, since all of the elements which are assembled to form the motor are of a simple circular shape machining from hardened materials is facilitated and case hardening or plating may readily be carried out because of wide tolerances inherent in the construction of the motor.

The rotors 40 may be readily formed from lightweight, wear resistant materials including plastics if desired.

The pressure of the drilling mud or other fluid employed must, of course, be very high because the fluid must carry the cuttings to the surface and move up-

wardly against a very large pressure head in many instances. However, as long as the inlet pressure in hose 31 is greater than that required to discharge the mud from the well the motor will operate efficiently because only a difference in pressure between said inlet and the outlet is required. It will be noted that the design of the motor is such that it will withstand high pressures even though only a relatively small differential pressure, sufficient to turn shaft 20, is applied to the motor structure.

The rotors 40 may be formed to a symmetrical annular shape if desired by providing the shaft with integral eccentric portions as indicated in the modified form of FIG. 5.

In this modified form of the invention the shaft 60 is formed with a plurality of integral eccentric portions 61 on each of which an annular rotor 62 is rotatably mounted. It will be seen that such a structure permits axial movement of the rotor relative to the shaft as in the preferred form. However with the structure of FIG. 5 it is not necessary to key the shaft to the rotor or to secure it in any other manner. Axially extending holes 63 similar to holes 46 are provided in eccentric portions 61.

The number and size of the holes 46 in rotors 40 may be increased substantially over that shown in FIGS. 2-4 since the load applied thereto is not substantial.

Although the particular embodiment above described provides for axial flow of the discharge fluid in one direction only, it will be apparent that in other applications of the invention axial flow in opposite directions may be permitted. In the structure of FIG. 1 such a modification may be accomplished by substituting an apertured plate similar to bottom plate 7 for the top plate 6.

The invention is particularly adapted for use as a water driven motor in locations where a head of water is available and it is desired to convert the water power by means of an inexpensive, readily assembled motor which requires a minimum of attention. Although the efficiency of this motor may not compare favorably with water turbines generally employed in hydroelectric plants, the above mentioned advantages make the present invention practical in many instances, such as in geographically remote locations, where a complicated and expensive turbine would be impractical.

I claim:

A fluid driven motor comprising:
 a shaft,
 a casing formed with a plurality of cylinders axially spaced along said shaft
 bearings on opposite ends of said casing for rotatably supporting said shaft,
 a plurality of rotors respectively received in said cylinders
 said rotors each being secured to said shaft for rotation therewith
 said cylinders each being formed by a pair of opposed endwalls on opposite sides of a rotor and a circumferentially extending cylindrical sidewall concentric with the axis of said shaft,
 said endwalls each being provided with a central opening and being in lapping relationship at all times with the adjacent faces of said rotor,
 a discharge nozzle in each of said sidewalls for directing fluid into each said cylinders in a direction generally tangentially thereof
 the outer cylindrical periphery of each of said rotors being eccentric to the axis of said shaft and being smaller in diameter than the inner diameter of the adjacent sidewall to define a circumferentially extending unobstructed passageway of varying radial extent between said rotor and said sidewall.
